COMBINATION BOAT FENDER BOARD AND
LIFE PRESERVER

Jesse E. Miller, Los Angeles, Calif.
(6633 Woodley Ave., Van Nuys, Calif. 91406)

Filed Jan. 13, 1969, Ser. No. 15,326

Term of patent 14 years

Int. Cl. D12—14

U.S. Cl. D71—1

FIGURE 1 is a front perspective view of a combination boat fender board and life preserver, showing my new design;

FIGURE 2 is a front elevational view thereof;

FIGURE 3 is a rear elevational view thereof;

FIGURE 4 is a side elevational view thereof as seen from the right in FIGURE 2; the other side, not shown, is a mirror image thereof;

FIGURE 5 is a perspective view thereof in another position;

FIGURE 6 is a plan view thereof as seen from the top or bottom in FIGURE 5; and

FIGURE 7 is an elevation view thereof as seen from either end in FIGURE 6.

I claim:

The ornamental design for a combination boat fender board and life preserver, substantially as shown and described.
